UNITED STATES PATENT OFFICE.

ENOCH S. MOORE AND HERBERT H. THOMAS, OF PARKERSBURG, WEST VIRGINIA.

CASING-HEAD ATTACHMENT.

1,281,808.

Specification of Letters Patent. Patented Oct. 15, 1918.

Application filed April 5, 1918. Serial No. 226,872.

To all whom it may concern:

Be it known that we, ENOCH S. MOORE and HERBERT H. THOMAS, citizens of the United States, residing at Parkersburg, in the county of Wood and State of West Virginia, have invented certain new and useful Improvements in Casing-Head Attachments, of which the following is a specification.

This invention relates to improvements in well drilling appliances and it is the principal object of the invention to provide a novel form of closure for casing heads whereby drilling operations can be continued after oil or gas has been reached and is flowing, without liability of waste and to also allow the tools employed in such drilling operations to be removed and replaced as it becomes necessary without waste.

Another and equally important object of the invention is to provide a closure which can be automatically disengaged from the casing head upon the raising of the tools to facilitate their removal and automatically engaged and locked in its engagement with the casing head upon the insertion of tools and the bailing line.

It is also an object of the invention to provide the device with cut-off means whereby the flow of oil to the casing head or through the same to the outlet pipes can be controlled at will by an operator.

Other objects will be in part obvious and in part pointed out hereinafter.

The invention consists, furthermore, in the novel arrangements and combinations of the parts of the device, as well as in the details of the construction of the same, all of which will be more fully described in the following specification and then finally embodied in the clauses of the claim, which are appended to this specification and which form an essential part of the same.

The invention is clearly illustrated in the accompanying drawings, in which:

Figure 1 is a side elevation of a casing head provided with the improved form of closure,

Fig. 2 is a vertical section therethrough,

Fig. 3 is a similar view having parts in elevation taken at substantially right-angles to Fig. 2,

Fig. 4 is a disassembled detail in perspec-

tive of the locking levers and the nut for locking the same, and

Fig. 5 is a detail in elevation of the connection between the valve element and the operating lever therefor.

Having more particular reference to the drawings, in connection with which like reference characters will designate corresponding parts throughout the several views, 1 represents the casing head to which the improved device is applied and 2 that portion of the casing which is engaged thereby. Said casing head is formed with an annular portion or valve seat 3 having outlet openings formed in its opposite sides, which openings are screw threaded and have the usual outlet pipes 4 turned into engagement therewith. Bearing trunnions 5 and 6 are formed concentrically of the end walls of the seat 3 and serve to pivotally support segmental valves 7 and 8, which valves have their respective arms provided with longitudinally disposed slots 9. Formed in certain of the adjacent marginal portions of the segmental valves are alined recesses 10, which as will be understood, serve to receive the usual bailing line, hereinafter mentioned, therethrough, at times. Packing strips 11 are carried upon the remaining marginal portions of said segmental valves 7 and 8 and are adapted to be engaged, at times, in order that said valves will form an effectual closure for the upper portion of the casing head when the improved closure, hereinafter more fully described, is removed therefrom.

To effect movement of the segmental valves 7 and 8, a yoke member 12 is provided and as will be noted, is slidably received about the bearing trunnion 6 and carries upon its opposite sides pins 13 which are adapted to be slidably engaged in the longitudinal slots 9 formed in the adjacent portions of the arms of the segmental valves. To the upper end of the yoke 12 a right angularly formed arm 14 is engaged and as will be noted, is passed through a suitable form of packing gland 15; the free end of said rod being pivotally connected to a link 15 having connection as at 16 with an operating lever 17 mounted on one side of the casing head adjacent the seat 3. A curved guard 18 formed with spaced seats is provided and as will be understood, serves as means for allowing

the operating lever 17 to be locked in adjusted position with relation to the casing head. Further, a second guard 19 is secured to one side of the casing head and arranged over a portion of the operating lever 17 in proximity to the pivotal mounting thereof, thus, serving as means for limiting movement of the same to a certain extent. Obviously, by rocking the operating lever 17 10 the slideable yoke 12 may be raised and lowered with respect to the interior of the casing head and the seat 3 and as a consequence, the segmental valves 7 and 8 engaged thereby will be moved with the same to different 15 positions, the same depending of course upon the direction of movement and the extent of movement of the operating lever.

Receivable in the open upper end of the casing head 1 is the improved closure 20 20 which as will be noted, is formed with radially disposed ways 21 having latches 22 slidably arranged therein, the outer ends thereof being beveled as at 23, for a purpose which will be hereinafter apparent. Loosely 25 engaged in openings formed in the rear portions of the latches 22 are the ends of bell crank levers 24. As will be noted, the closure 20 is formed with a concentrically disposed cable receiving way or passage, which 30 in turn has a tubular member 25 slidably arranged therein the opposite ends of which are screw threaded in order that nuts 26 and 27 can be turned into engagement with the same. In this connection, it is to be noted 35 that the upper extremity of the element 25 is reduced and has a locking nut 28 arranged thereon, which nut is formed with recesses 29 adapted, at times, to aline with the adjacent ends of the bell crank levers 24 in 40 order to permit free pivotal movement of the same. To facilitate rotation of the nut 28, a handle member 28' may be and preferably is arranged thereon. Displacement of the locking nut 28 is prevented by reason 45 of its engagement with the adjacent portion of the nut 26. The lower nut 27 has engagement with the lower convolution of an expansible coil spring 30, the upper convolutions of which have bearing upon the adjacent portion of the closure 20. In this 50 connection, it is to be also understood that the nut 27 is of a size such as will permit the same to be employed as a stop adapted to be engaged by the tools or bailer arranged in the casing, at times, whereby 55 movement will be imparted to the element 25. A second tubular element 31 is slidably engaged about the element 25 and has a disk 32 engaged with its upper end, which disk 60 is normally disposed beneath the free ends of the bell crank levers 24. To insure fluid tight connection between the tubular member 31 and the closure 20, a suitable form of packing gland designated by the number 65 33 may be and preferably is provided.

To prevent the waste of oil and gas by reason of the passage of the cable 34 into the casing head, a tubular member 35 is arranged about the same and has connection with a suitable form of packing gland 36 70 at its upper end. Hence, oil will be removed from the cable during its movement through the tubular member 35 and the gland 36.

To permit the seating of the closure 20 in the open upper end of the head 1, the same 75 is rabbeted as at 37 and provided with a suitable form of annular packing, while an annular groove having one wall thereof beveled is arranged in the side of the rabbeted portion and is adapted to be engaged 80 by the slideable latches 22, said groove being indicated by the numeral 38. It will be noted in this connection, that the beveled ends 23 of the latches 22 will engage with the beveled wall of the annular groove 38 85 and as a consequence, said closure will be caused to firmly seat on the annular packing arranged in the head.

In operation, the tools are inserted into the casing 2 and the cable 34 is passed 90 through the way formed in the closure 20, whereupon said closure is engaged with the open upper end of the casing head and the latch members 22 are moved outwardly due to their connection with the levers 24, which 95 levers will, in turn, have their free extremities engaged by the locking nut 28 carried upon the upper end of the tubular member 25, which nut is of course turned to cause disalining of the recesses 29 with the adjacent ends of said levers 24. Should oil or 100 gas be reached and it be desired to continue drilling operations during the flowing of the oil or gas or both, the operating lever 17 is moved downwardly to cause corresponding movement of the segmental valves 105 7 and 8, which as will be understood, move to positions about the cable 34 and the tubular member 35, thereby uncovering the outlet pipes 4 and allowing the oil or gas flowing through the casing head to pass through the outlet pipes. When the tools are withdrawn, the same engage the nut 25, thus moving the tubular members 25 and 31 upwardly and causing the slideable latches 22 110 115 to be moved inwardly by reason of the movement of the bell crank levers 24. With the latches thus disengaged, the closure 20 may be readily removed from the casing head and as a consequence, the tools also 120 removed therefrom. To prevent the oil or gas from flowing from the casing head upon the removal of the closure 20 therefrom, the operating lever 17 is rocked to its uppermost position, thereby causing the segmental 125 valves 7 and 8 to move to their uppermost positions over the upper portion of the seat 3, thus closing the upper end of the casing 1 and causing the oil and gas to flow 130 through the outlet pipes 4.

Manifestly, the construction shown is capable of considerable modification and such modification as is within the scope of our claims, we consider within the spirit of 5 our invention.

We claim:

1. The combination with a casing head, of a closure therefor having a cable passage, slideable latch means on said closure, 10 levers mounted on the closure having engagement with said latch means, means on the closure for locking the levers, and other means slideable about said locking means and engageable with the levers for releasing the 15 same, at times.
2. The combination with a casing head, of a closure therefor, slideable latch members arranged on said closure, said closure having a cable passage therein, levers mounted 20 on the closure engaged with said latch members, tubular means slidably arranged in the cable passage, means connected to the tubular means, engageable with the levers for locking the same, and other tubular 25 means slideable on said first tubular means and engageable with the levers for releasing the same, at times.
3. The combination with a casing head

having a valve seat formed therein and outlet pipes communicating therewith, of segmental valves rotatably mounted in the head adjacent the seat provided with slotted arms, a yoke slideable in the casing having connection with said arms, and means arranged exteriorly of the casing and connected to said yoke for operating the same. 30

4. The combination with a casing head having a valve seat formed therein and outlet pipes communicating therewith, of a closure for the same having a cable passage, 40 slideable latch means on said closure, levers on the closure having engagement with said latch means, means depending from said closure for locking the levers, other means depending from the closure for releasing the 45 levers, at times, segmental valves rotatably mounted in the casing adjacent said seat and provided with slotted arms, a yoke having connection with said slotted arms, and means arranged exteriorly of the casing and 50 connected to said yoke for operating the same.

In testimony whereof, we affix our signatures hereto.

ENOCH S. MOORE.
HERBERT H. THOMAS.
